DESIGN FOR A SEPARABLE BROOCH

Adolph Katz, Providence, R. I., assignor to Cohn & Rosenberger, Inc., New York, N. Y., a corporation of New York

Application August 12, 1942, Serial No. 107,913

Term of patent 3½ years

To all whom it may concern:

Be it known that I, Adolph Katz, a citizen of the United States of America, residing in Providence, county of Providence, and State of Rhode Island, have invented a new, original, and ornamental Design for a Separable Brooch, of which the following is a specification, reference being had to the accompanying drawing, forming part thereof.

Fig. 1 is a plan view of a separable brooch showing my new design.

Fig. 2 is an edge view thereof.

Fig. 3 is a plan view in separate position.

I claim:

The ornamental design for a separable brooch, substantially as shown.

ADOLPH KATZ.
